UNITED STATES PATENT OFFICE

FRED P. BENJAMIN, OF WATSEKA, ILLINOIS

RADIO RECEIVING SYSTEM

Application filed May 23, 1927. Serial No. 193,688.

This invention relates to radio receiving systems and is an improvement over the system described and claimed in my copending application Serial No. 75,425, filed December 5, 14th, 1925.

In my copending application above referred to I have shown and described a system which is an improvement over the usual receiving sets in that it minimizes the usual 10 howls, squeals and whistles often caused by the generation of eddy currents and harmonics. The improved results are obtained without introducing losses and without the use of any neutralizing, balancing or bridging action or the like. In accomplishing the 15 desired results, the efficiency of the action of the grids of the electron discharge tubes is greatly increased by providing a freer flow of current thereto.

20 It has been found that the present invention provides a system which embodies the advantages of the system shown in my copending application, and also provides the additional advantage of minimizing the 25 transmission of plate current to the grids, and consequently minimizes the consumption from the "B" battery or other source employed. An important object of the invention therefore is to accomplish the results obtained by the system illustrated and described 30 in my copending application and to further increase the accuracy of signal reception by decreasing the transmission of plate voltages to the grids of the tubes.

35 A further object of the invention is to render practicable a double grid-filament circuit, through a common transformer, with lessened capacity effect between the two leads.

40 A further object is to provide a double grid-filament circuit to permit the various electric currents passing through such circuits to find the route most suitable for its function.

45 Other objects and advantages of the invention will become apparent during the course of the following description.

In the drawing I have shown one embodiment of the invention. In this showing the single figure of the drawing is a diagrammatic view wherein for the purpose of illus-

tration the invention is shown as applied to a single stage of tuned radio frequency.

Referring to the drawings the numeral 10 designates the usual antenna 10 connected by a lead 11 to one end of a coil 12 of the usual type. The other end of this coil is connected by a lead 13 to a suitable ground 14, as shown. The coil 12 constitutes the primary of a radio frequency transformer which includes a pair of secondary coils 15 and 16. The coil 15 preferably includes substantially the same number of turns as the primary 12, while the coil 16 includes a greater number of turns, depending upon the wave band to be covered.

The numeral 17 designates an ordinary electron discharge tube provided with a plate 18, grid 19 and filament 20, the latter being provided with positive and negative leads 21 and 22 respectively. A wire 23 is connected to the negative lead of the filament and is in turn connected to one end of the secondary coil 16 by a lead 24. The grid 19 is connected to a lead wire 25, which, in turn, is connected to the opposite end of the secondary 16 75 through a lead 26, and a fixed capacity 27 is arranged in this lead. A variable capacity 28 is connected across the leads 24 and 26 by wires 29 and 30 respectively.

The usual "A" battery 31 is employed, the negative side of which is connected to the lead 23 as shown. The positive terminal of the "A" battery is connected to the negative terminal of a "B" battery 32 by a wire 33, in the usual manner. A lead wire 34 is connected at one end to the connecting wire 33 and is adapted to supply current to the positive side of the filament through a suitable rheostat 35. One side of the smaller secondary 15 is connected to the wire 34 by a lead wire 36, 90 while the opposite end of the coil 15 is connected to the grid lead 25 by a wire 37, a resistance 38 being arranged in the lead 37 for a purpose to be described.

The radio frequency stage illustrated is 95 adapted to be coupled to a succeeding stage in the usual manner. As shown, the positive side of the "B" battery is connected to one end of a wire 39, and the opposite end of this wire is connected to one end of a transformer 100

primary coil 40. The opposite end of the coil 40 is connected to the plate 18 by a lead wire 41. It will be apparent that the coils 12, 15 and 16 are arranged in inductive relation and that the coil 40 may be arranged in a similar relation to a succeeding stage of radio frequency, or a detector, the succeeding stages preferably employing the double grid circuit previously described, in which the two secondary coils 15 and 16 are arranged. The same system is adapted to be used in connection with not only the radio frequency stages and the detector but also to one or more succeeding stages of audio frequency.

It has been found that the provision of the dual transformer primary coils provides multiple grid returns permitting a freer flow of current to the grids of the tubes thus materially reducing the generation of eddy currents and greatly improving the quality of reception. The function of the capacity 27 is to prevent "B" battery current from passing through this coil and impressing itself upon the grid. Since returns are made to each filament lead, this capacity also prevents a short circuit across the "A" battery. The function of the resistance 38 inserted in the other grid-filament circuit is to limit the amount of "B" battery current that may reach the grid through any tendency to complete its circuit by crossing between the grid and plate and also to decrease the capacity effect between the two secondaries of the transformers. It is believed that the total elimination of grid leakages through one of the grid circuits has a strong influence on the satisfactory results obtained from the use of the circuit. The resistance referred to also tends to decrease if not eliminate any necessity for tuning the coil to which it is connected and further permits the number of turns in this coil to be decreased in number to that employed in the usual primary coil, or even less, allowing the common transformer to be constructed with great simplicity and without undue capacity effect between the coils. While the insertion of the capacity 27 in the tuned grid circuit somewhat impairs grid action, the other grid circuit through the coil 15 acting in conjunction with the tuned circuit, overcomes the defect referred to and provides a greatly improved grid action with completeness and accuracy of tone much superior to that of the usual single grid-filament circuit.

The action of the resistance 38 is unique in that within the limits of practical values, such as 1/20 megohm to 20 megohms, volume increases as the resistance is increased, having the opposite effect of resistances in general probably due to the fact that it serves to limit the amount of plate current traveling in an opposite direction to the currents normally in the grid-filament circuit. Increased resistance therefore is desirable, and it also is de-

sirable for the reason that a decrease in resistance might tend to detune the transformer. The resistance 38 also provides a circuit better adapted to audio frequency currents, and handles with less confusion the detection which takes place to a greater or less extent in any radio frequency circuit.

The combination of the tuned grid circuit, including the capacity, with the other grid circuit, including a high resistance, retains the benefits of both, and yet provides an interaction which offsets the disadvantages of either thus permitting reproduction of sound with greater faithfulness and with less tendency toward oscillation than in the usual grid return circuit. The return through what might be termed the auxiliary circuit, that is, the circuit through the coil 15 to the positive side of the filament has the additional feature of lessening the tendency of plate current to pass to the grid through the "A" battery in common with the filament circuit, as well as through the negative side of the filament, and in multiple tube receiving systems, it lessens the tendency of feed-back affecting the action of the previous tube, reducing still further the tendency toward oscillation. Some gain in clearness also results from the provision of leads from the grid to opposite sides of the filament.

The circuit illustrated shows what might be termed the main grid circuit, that is, the circuit through the coil 16, tuned by a variable capacity, but the invention is applicable to any other method of tuning, such as by a variometer or vario-coupler. The invention is readily applicable to detector, radio frequency and audio frequency circuits, and thus obviously may be applied to one tube of a multi-tube circuit or to all of the tubes thereof.

The words "main" and "auxiliary" are employed merely for the purpose of description, and as a matter of fact the circuit operating most strongly will depend upon the respective values of resistance and capacity employed.

The circuit illustrated is to be considered only as one embodiment of the invention, and it is to be understood that the connections of the leads from the secondaries of the transformer to the filament of the tube may be varied. In other words, the particular connections illustrated are not vital to the proper operation of the circuit. For instance, the positions of the capacity 27 and resistance 38 may be reversed, and they may be arranged at any desired point in their respective circuits. The capacity of the variable condenser 28, and the number of turns of wire employed in making the transformers will depend, of course, upon the range of frequencies which it is desired to receive. As previously stated, the resistance 38 is not critical, but it is desired to employ a fairly high resistance within the range outlined above. It also has been found that the capacity 27 also is not par-

ticularly critical. The several coils of the filament transformer may be wound independently on their forms, or the secondaries of each transformer may be wound as a pair. It also will be apparent that a single form may be employed if desired.

I claim:

1. In a radio receiving system, an input circuit, an electron discharge tube having a cathode and grid therein, and a pair of leads each including a transformer secondary coil inductively associated with the input circuit, said leads being connected between the grid and cathode of the tube, each of said leads including means tending to prevent the flow of direct current therethrough.

2. In a radio receiving system, an input circuit, an electron discharge tube having a cathode and grid therein, a pair of leads each including a transformer secondary coil inductively associated with said input circuit, said leads having a common connection at one end with the grid of the tube, the opposite ends of said leads being connected to the cathode of the tube, a capacity arranged in one of said leads, and a resistance arranged in the other of said leads.

3. In a radio receiving system, an input circuit, an electron discharge tube having a filament and grid therein, a pair of leads having a common connection at one end with the grid of the tube, the opposite ends of said leads being connected respectively with opposite ends of the tube filament, a capacity connected in one of said leads, and a resistance connected in the other of said leads, each of said leads including a coil winding inductively associated with said input circuit.

4. In a radio receiving system including an electron discharge tube having a cathode and grid therein and a primary transformer coil, a pair of secondary transformer coils inductively associated with said primary coil, a pair of leads having a common connection at one end to the grid of the tube, each of said secondary coils forming a portion of one of said leads, the opposite ends of said leads being connected to the cathode of the tube, a capacity arranged in one of said leads, and a resistance arranged in the other of said leads.

5. In a radio receiving system including an electron discharge tube having a filament and grid therein, and a primary transformer coil, a pair of secondary coils arranged in inductive relation to said primary transformer coil, a pair of leads having a common connection at one end with the grid of the tube, each of said secondary coils forming a part of one of said leads, the opposite ends of said leads being connected respectively to the opposite ends of the tube

transformer, a variable capacity connected across one of said secondary coils, a resistance arranged in one of said leads, and a fixed capacity arranged in the other lead.

6. In a radio receiving system including an electron discharge tube having a filament and grid therein, and a primary transformer coil, a pair of secondary transformer coils inductively associated with said primary coil, one of said secondary coils including a suitable number of turns to cover the desired broadcast band, the other of said secondary coils including a number of turns insufficient for tuning, a pair of leads having a common connection at one end to the grid of the tube, each of said secondary coils forming a part of one of said leads, the opposite ends of said leads being connected respectively to the opposite ends of the tube filament, a variable capacity connected across said first mentioned secondary coil, a capacity arranged in one of said leads, and a resistance arranged in the other of said leads.

7. In a radio receiving system including an electron discharge tube having therein a grid, and a filament provided with positive and negative terminals, and a primary transformer coil, a pair of leads having a common connection at one end with the grid of the tube, the opposite end of one of said leads being connected to the positive terminal of the filament, the opposite end of the other of said leads being connected to the negative terminal of the filament, a secondary transformer coil arranged in said first mentioned lead and including an insufficient number of turns for tuning, a secondary coil arranged in said second mentioned lead and including a sufficient number of turns to be tuned to cover the desired broadcast band, a variable capacity connected across said last named secondary coil, a resistance arranged in said first mentioned lead, and a capacity arranged in said second named lead.

In testimony whereof I affix my signature.
FRED P. BENJAMIN.
